FISHING LURE

Jake Street, Fort Worth, Tex.

Application October 19, 1956, Serial No. 43,428

Term of patent 14 years

(Cl. D31—4)

FIG-1

FIG-2

FIG-3

FIG-4

Figure 1 is a top plan view of a fishing lure, embodying my new design.

Figure 2 is a side elevational view thereof.

Figure 3 is an inverted plan view thereof, and

Figure 4 is a front elevational view of the fishing lure with the diving vane adjusted for swimming at a greater depth.

I claim:

The ornamental design for a fishing lure, substantially as shown.
